UNITED STATES PATENT OFFICE.

HARRY M. CRAWFORD, OF BOSTON, MASSACHUSETTS, ASSIGNOR TO WARREN STETSON,
TRUSTEE, OF BOSTON, MASSACHUSETTS.

WINDOW-FASTENER.

977,854.

Specification of Letters Patent.

Patented Dec. 6, 1910.

Application filed March 5, 1910. Serial No. 547,546.

To all whom it may concern:

Be it known that I, HARRY M. CRAWFORD, a citizen of the United States of America, and a resident of Boston, in the county of 5 Suffolk and State of Massachusetts, have invented certain new and useful Improvements in Window-Fasteners, of which the following is a specification.

This invention relates to window fasteners and has for its object the production of 10 a window fastener which is adapted to lock the two sashes together when in closed position or to lock them together when moved slightly relative to each other so that the 15 windows may be opened either at the bottom or at the top a sufficient distance to ventilate the room and still prevent any person from entering or reaching through the opening and unlocking the fastening members which secure the two sashes together. 20

The invention consists in certain novel features of construction and arrangement of parts which will be readily understood by reference to the description of the drawings 25 and to the claims hereinafter given.

Of the drawings: Figure 1 represents a section through a portion of an upper sash showing in plan a portion of the lower sash and the fastening members secured to said 30 sashes, and Fig. 2 represents an elevation of the same with the sashes moved relative to each other and locked together.

Similar characters designate like parts throughout the drawings.

In the drawings, 10 represents a portion 35 of the upper member of the lower sash and to the upper face of this member is secured a support 11 by means of the screws 12. Projecting from the upper face of this support is a headed guide member or stud 13, the shank of which passes through a slot 14 in a sliding bolt 15. To the upper face of the lower member 16 of the upper sash is secured a socket member 17 by means of 40 screws 18. This socket member is provided with a slot 19 extending upwardly through one side wall thereof and partially across the upper wall thereof, as indicated plainly in Figs. 1 and 2. Extending through this 45 slot 19 is a shank 20 of a bar 21, the opposite end of the shank 20 being provided with a head 22 which prevents the disengagement of the bar 21 from the socket member 17. The bar 21 is provided with a plurality of 50 openings 23 therethrough with either one

of which the bolt 15 is adapted to engage when the bar 21 is in raised vertical position, as indicated in Fig. 2.

It is obvious that the sashes 10 and 16 may be moved relative to each other a short 60 distance and the bolt 15 moved upon the guide member 13 so that one end thereof will pass through an opening 23 and lock the two sashes together so that further movement relative to each other is pre- 65 vented. When this has been accomplished the sashes will be effectively locked together so that they may be moved to the upper part of the window frame leaving an opening at the bottom for the admission of the fresh 70 air or moved to the bottom of the window frame leaving an opening at the top for the exit of the dead air from the room.

A yielding member such as a spring 24 is secured to the support 11 and normally ex- 75 tends upwardly into the path of the bolt 15 so as to prevent movement thereof, when in engagement with the socket member 17 to lock the window sashes together when the window is closed or in engagement with one 80 of the openings 23 when the window is partially opened. When it is desired to unlock the window the operator presses down the yielding member 24 and moves the locking bolt along the guide member 13 until the 85 bolt has been wholly removed from the socket member 17 or the opening 23. When the bolt 15 has been withdrawn from the socket member 17 it is moved about the vertical flanged projection 13 into a position at 90 right angles to its locking position and while in this position the side wall of the yielding abutment 24 will contact with the side wall of the bolt and prevent its accidental displacement by turning around the projection 95 13. By this means the ends of the bolt when disengaged from the socket can never protrude beyond the window sash 10 and thereby become injured or cause an injury to any of the other members forming a part of the 100 window sashes or the locking mechanisms therefor.

One flange of the socket member 17 is provided with a lug 25 which positions the bar 21 when not in use and prevents it from accidentally moving into the plane of movement of the lower sash 10. Normally the bar 21 rests upon the lower member of the upper sash frame, as indicated in Fig. 1, and when in this position the head 22 of the 110

shank 20 is in the position shown in said figure and in dotted lines in Fig. 2, in which position the locking bolt 15 is free to move into the socket 17 as shown in Fig. 1, and 5 when thus positioned one side wall of the locking bolt engages with the outer face of the head 22 and prevents any displacement of said bar 21.

The bar 21 is cut away as at 26 on an angle to the shank 20 so that when the bolt 15 has been removed from the socket 17 the bar 10 may be turned into a position at right angles to its position shown in Fig. 1, and then moved along the slot 19 until it assumes the 15 position shown in Fig. 2, in which position it is adapted to receive into one of the openings 23 the end of the bolt 15, as heretofore described.

It is believed that the operation and many 20 advantages of the invention will be fully understood from the foregoing.

Having thus described my invention, I claim:

1. In a device of the class described, the 25 combination with a socket secured to one sash; of a pivot secured to the other sash, a bolt slidably mounted on said pivot and adapted to be moved into a position at right angles to its locking position; and a yielding 30 abutment adapted to engage the end of said bolt when positioned within said socket and the side of said bolt when withdrawn from said socket and thereby prevent its accidental displacement.

35 2. In a device of the class described, the combination of a support secured to one window sash and provided with a flanged member; a locking bolt provided with a slot through which said flanged member extends; a socket secured to the other sash and adapted 40 to receive the end of said locking bolt; and yielding means for retaining said bolt in locking position and adapted to co-act with the side of said bolt when withdrawn

from said socket thereby preventing its accidental displacement. 45

3. In a device of the class described, the combination of a socket secured to one sash; of a support secured to the other sash and provided with a vertical projection; a bolt 50 thereon having both a pivotal and slidable movement about said projection; and means for positively retaining said bolt in both its locking or inoperative position and preventing its accidental displacement. 55

4. In a device of the class described, the combination of a socket secured to one sash; of a support secured to the other sash; a vertical projection thereon, a bolt thereon having both a pivotal and slidable movement 60 about said projection; and a flat spring extending transversely of said support, one side of which is adapted to engage the end of said bolt when inserted in said socket and prevent its accidental displacement. 65

5. In a device of the class described, the combination with a socket secured to one sash; of a support secured to the other sash and provided with a transverse depression in its upper face; a bolt secured to the upper 70 face of said support and slidable thereon transversely of said depression and adapted to be turned into a position at right angles to its locking position; and a flat spring secured in said depression and normally extending above the upper face of said support in position to engage the end of said bolt and prevent its withdrawal from said socket when in locking position and to engage with the side face of said bolt when 75 withdrawn from said socket and turned into a position parallel to said flat spring. 80

Signed by me at 4 Post Office Sq., Boston, Mass., this 2d day of March, 1910.

HARRY M. CRAWFORD.
